ROOF PITCH SIGHT GAUGE

Fred Hansen, White Plains, N. Y.

Application February 27, 1948, Serial No. 11,702

4 Claims. (Cl. 33—64)

1

This invention relates to measuring devices and more particularly to a roof pitch sight gauge for enabling an accurate estimation of the dimensions of a peaked roof from a position remote therefrom.

In calculating the surface areas of a peaked roof it is necessary to ascertain the up and over distance, i. e., the total width of the two sloping sides of the roof, which distance when multiplied by the length of the roof will result in the surface area. While the length of the roof is a dimension readily ascertainable from the ground, it being normally coextensive with the ground length of the building, the up and over distance is not coextensive with the ground width of the building but rather exceeds the ground width to an extent depending upon the peak angle, i. e., the angle at which the sloping sides of the roof meet. The device, according to the instant invention, provides adjustable means whereby the peak angle of a roof may be accurately sighted and related dimensions determined accordingly.

An object of the invention is to provide an improved sight gauge adjustable in conformance with the gable end of a peaked roof for determining the pitch point of said roof.

A further object of the invention is to provide an adjustable roof sight gauge of simple and inexpensive construction and of small compact shape and size so as to be easily handled and readily adaptable for use as a mailing piece.

Other objects and features will become apparent from the following description when read in conjunction with the drawings wherein:

Fig. 1 is a general front view of the gauge as embodied in a foldable card or mailing piece.

Fig. 2 is a diagrammatic view illustrating the manner in which the gauge is used.

Fig. 3 is a detail view showing separately the indicia bearing sector element of the gauge.

Fig. 4 is a view showing the manner in which the structure may be folded for handling or mailing purposes.

With reference to the drawings and particularly to Fig. 1, it will be seen that the device, according to the present invention, may be embodied in a card shaped in the form substantially as shown so as to provide a rectangular center section 1 with flaps 2, 3 disposed at each side thereof. While card stock is deemed a preferable material for the device, it will be understood any like material having similar qualities of texture, rigidity and opaqueness may be employed. The side flaps 2, 3 are divided from the center section 1 by vertical fold or bend lines

2

4 and are adapted to provide a suitable surface which may be imprinted with any desired matter, not shown, such as advertising copy or the like so as to carry out the additional function of the device as a mailing or display piece.

Also projecting from the center section 1 of the card is a flap or tab 5 of substantially triangular shape having inwardly inclining straight side edges 6 and 7, respectively, said tab being divided from the remainder of the card by a horizontal bend or fold line 8.

Pivotal joined to the tab 5 at the apex thereof by a pivot pin 11 is a sector shaped member 12 having straight edges 13, 14, as can also be seen in Fig. 3. The pivotal connection between the sector 12 and the tab 5 may be of any suitable construction so as to enable rotatable adjustment of the sector relative to the tab, whereby varying roof peak angles may be simulated by the composite silhouette formed between tab edge 6 and the sector edge 14 when the device is used in the manner hereinafter more fully described.

The sector is provided with values in graduated scales 15, 16 arranged arcuately thereon and circumferentially of the pivotal axis thereof. Cooperating with said scales are viewing apertures 17, 18, formed in the tab 5 and disposed the same radial distances respectively from said pivotal axis as said scales so as to provide a fixed point for locating the related value in each scale corresponding to the adjusted position of the sector 12.

The manner in which the gauge may be used is illustrated in Fig. 2. As can be seen therein, the user may be positioned at any convenient point somewhat distant from the gable end of the roof to be measured. The gauge is held in a manner wherein the tab 5 will provide a silhouette over which the roof gable is sighted, the edge 6 of the tab being made to align with the side 19 of the roof. The sector 12 is then rotatably adjusted so that the edge 14 thereof aligns with the side 20 of the roof, whereby the peak angle of the roof will be duplicated in the gauge by the composite angle formed by the tab 5 and sector 12. From the scale 16 the pitch point of the roof will be indicated in the viewing aperture 18, said pitch point being indicated as a fractional value and being that portion of the width of the building by which the up and over dimension of the roof exceeds the width of the building. For example, in the present instance with the width of the building known to be twenty-four feet, and assuming the pitch point

found by the gauge to be, as shown in Fig. 1, $5/12$, then the up and over distance may readily be computed to be twenty-four feet plus ten feet or thirty-four feet. Thus, with the up and over distance known and the length of the building also a known quantity, the surface area of the roof may readily be computed.

If desired, a table may be provided for assisting in the computation, a diagrammatic table being shown in Fig. 1 and being imprinted on the center section 1 of the card. The table consists of up and over dimensions arranged in vertical and horizontal columns, each vertical column headed by and relating to a particular pitch point, each horizontal column relating to a particular building width dimension, the corresponding up and over distance being found at the point of intersection of any two respective columns.

It is also desirable to compute the height of a gable, i. e., the difference in elevation between that of the roof peak and that of the points at which the roof is joined to the side walls of the building. For this purpose, the scale 15 is provided, said scale indicating in cooperation with the aperture 17 in decimal quantities the proportional relation between the building width and the height of the gable. For example, in the present instance, assuming the pitch point is found to be $5/12$, the height of the gable would be, as indicated in Fig. 1, fifty hundredths of the building width of twenty-four feet or twelve feet. If desired, a table (not shown) but arranged similarly to that illustrated in Fig. 1 and heretofore described, may be provided on the card to similarly assist in the computation of the gable height dimension.

As can be seen in Fig. 4, the card, when not in use as a gauge, may assume the form shown with the tab 5 folded downwardly along the fold line 8 and with end flaps 2, 3 folded inwardly along lines 4. With the parts in this folded position, the tab 5 and sector 12 will be enveloped by the flaps 2, 3 and accordingly adequately protected against accidental mutilation, and the overall size of the card will be reduced to a conveniently small rectangular shape thereby facilitating the handling and use of the card as a mailing piece if desired.

While I have disclosed for illustrative purposes one form of the invention, I do not wish to be limited to the exact form herein shown and described nor to anything less than the whole of the invention as hereinafter claimed.

What I claim and desire to secure by Letters Patent is:

1. A roof pitch sight gauge comprising a straight edged sighting member, two adjacent edges thereof defining a substantially angular silhouette when held in sighting relation to a roof to be measured, a sector shaped member pivotally joined to said sighting member, said sector shaped member being rotatable in a plane parallel with said sighting member and adapted to form with said sighting member a composite angular silhouette adjustable in conformance with the peak angle of said roof being measured, and graduated markings arranged on one of said members circumferentially to the rotatable axis thereof for indicating values corresponding to the angle formed by the composite silhouette of said members in each adjusted position thereof.

2. A roof pitch sight gauge comprising a straight edge sighting member, two adjacent edges of said member defining a substantially angular silhouette when held in sighting relation to a roof to be measured, a sector shaped member pivotally joined to said sighting member in parallel planar relation thereto, one edge of said sector shaped member cooperatively forming with one edge of said sighting member a composite angular silhouette adjustably variable for aligning with the peak angle of said roof to be measured, and graduated markings arranged on one of said members circumferentially to the pivotal axis thereof for indicating values corresponding to the angle formed by the composite silhouette of said members in each adjusted position thereof.

3. A roof pitch sight gauge comprising a straight edged sighting member, two adjacent edges of said member defining a substantially angular silhouette when held in sighting relation to a roof to be measured, a sector shaped member disposed in parallel planar relation to said sighting member, one edge of each of said members cooperatively defining an angular composite silhouette, and pivot means interconnecting the apexes of said members for enabling rotatable adjustment of said composite silhouette in conformance with the peak angle of said roof to be measured, one of said members having graduated scales of values arranged thereon circumferentially to said pivot means, the other of said members having apertures formed therein and aligned with said scales, said apertures being adapted to expose and indicate a particular value in each scale corresponding to the angle formed by the composite silhouette of said members in each adjusted position thereof.

4. A roof pitch sight gauge comprising an elongated card having bend lines interconnecting opposing edges thereof, said bend lines dividing the surface of said card into a rectangular section and tabs foldable upon said rectangular section, one of said tabs being of substantially triangular shape and adapted in an unfolded extended position to define an angular silhouette when held in sighting relation to a roof to be measured, a sector shaped card pivotally connected to said one tab at the apex thereof, one edge of said sector shaped card defining in cooperation with one edge of said one tab a composite angular silhouette adjustable in conformance with the peak angle of said roof to be measured, and indicating means for determining roof measuring values relating to the angle of said composite silhouette, said means including a graduated scale imprinted in circumferential arrangement on said sector shaped card and a viewing aperture aligned with said scale and formed in said triangular shaped tab.
